BRISTLE FEEDING AND PICKING DEVICE

Leroy W. Vinal, Leominster, Mass., assignor to
E. I. du Pont de Nemours & Company, Wil-
mington, Del., a corporation of Delaware

Application June 7, 1938, Serial No. 212,371

9 Claims. (Cl. 300—7)

The principal objects of this invention are to provide a bristle feeding device with a hopper arranged so it can be filled with bristles without stopping the machine and to provide means whereby a movable bottom for the hopper is oscillated on a pivot near the top thereof for consolidating the bristles in the lower part, which is of gradually reduced area toward the end, and to press the bottom against the picker so that the picker may be enabled to pick up enough bristles to form a tuft; to provide an end for the hopper which will bear by spring pressure on the surface of the picker and prevent the loss of bristles at this point and also bring them to a position to be fed into the slot in the picker; to provide the above features in combination with an oscillating picker, and to provide the picker with means for adjusting both the depth of the slot for receiving the bristles and the position of the slot at the delivering point.

Other objects and advantages of the invention will appear hereinafter.

Reference is to be had to the accompanying drawings, in which

Fig. 1 is a perspective view of a hopper for feeding bristles, or the like, and associated parts illustrating a preferred form of this invention, and

Fig. 2 is a side view of the same, partly in section.

This hopper and bristle feeding device is intended to be attached to a tuft forming and setting machine and to constitute an important part thereof. In the form shown, the hopper is supported by a part of the frame 10 of such a machine and the hopper proper is carried partly by a bracket 11 on that frame. The hopper comprises two sides 12, each one having a vertical slot 13 therein. At one side of the hopper is a bracket having a screw 14 on a horizontal arm 15 which, at its outer end, has a pivot screw 16 carrying a bar 17. This bar passes through the two slots 13.

The other two sides of the hopper are fixed in place by screws 19 or the like. As the bristles feed down, the bar 17 feeds down naturally and the intention is that this bar should always apply a little pressure to the bristles in the hopper to keep them consolidated and eliminate important interstices between the bristles and to keep them from mixing up in the top part of the hopper. The bar 17 can be raised above its pivot to allow the hopper to be loaded with bristles while the machine is operating.

Toward the lower end of the hopper is a pivot

20 carrying a generally inclined and curved plate 21 constituting the bottom of the hopper. For the purpose of preventing the escape of bristles, there is a projection 22 up from this bottom which extends up into a slot 23' in the bottom 5 of one of the sides 12. This bottom extends down to a point below the lower end 18 at the opposite side 12 of the hopper and the shape and curvature are such that the space between which the bristles are discharged against the picker 23 10 grows gradually less toward the discharge end of the hopper. This discharge end is closed by a stationary member 24 having within it a spring-pressed plunger 25. The spring behind this plunger keeps a curved surface 26 at the end of 15 the plunger constantly in contact with the arcuate end of the picker. Therefore, at no time is there any chance for the bristles to get out of the hopper over this plunger.

The bottom wall 21 of the hopper is provided 20 with a concave end projection 33 which receives the end of a screw 27 carried by a bell crank 28 having on the other arm thereof a projection 29 which is operated by a cam 30 on a shaft 31. The result of this construction is that, where the 25 cam is shown, the bell crank 28 will remain stationary until the cam turns to such position as to bring into operation the sinuous outline 32 of the cam. Now the bell crank will be oscillated and the bottom 21 will also be oscillated toward 30 and from the picker 23. The shortest distance between the picker and the bottom of the hopper is controlled by the screw 27 which supports the bottom 21. The picker 23 is operated by a link 40 which is actuated by a cam (not shown) 35 in a well known manner, and in a certain relationship to the shaft 31 so that, during the forward motion of the picker after the slot has passed out of the hopper, the bottom 21 will be constantly oscillated to settle the bristles and 40 compact them in the bottom of the hopper. The bottom 21 is under the influence of the concentric portion of the cam during the backward stroke of the picker and is being forced up to hold the bristles firmly against the picker. 45

It will be seen also that, from the stationary frame 25 on which the stationary member 24 is mounted, there is a spring 36 which also engages a projection on the bell crank which operates the bottom 21. Therefore, this spring 36, at every 50 opportunity, presses the bottom 21 backwardly against the screw 27 and the projection 29 inwardly toward the cam 30.

There is an adjustable screw stop 44 for controlling the end of the stroke of the picker 23 55

and another adjustment screw 37 for adjusting the depth of the picker slot 39.

Link 40 has connected thereto a slide 41 running in a guide in the picker, and said slide is provided with a lateral projection 48 which reciprocates in a slot 49 in the picker. At the ends of the slot 49, there are provided the shoulders 50 and 51 which projection 48 abuts to drive the picker 23 in either direction with a slight lost motion at each end of the stroke. The projection 48 also mounts the separator knife 42 which closes the bristle slot 39 at appropriate intervals and separates excess bristles from the tuft in the slot.

15 The bristles which are carried downwardly by the picker from the slide 41 are released into a slot 45 in a support 46. Here, a needle 47 comes down in the center, doubles the bristles into a tuft, and forces them, if desired, into a previously 20 prepared brush back in the usual way. Of course, a wire (not shown) is introduced transversely into the center of the tuft of bristles, as usual.

With the picker as shown in Fig. 2, the end of 25 the down or clockwise stroke has been substantially reached and at this point the link 40 and attached projection 48 start on their upward or counter-clockwise movement, thus withdrawing the knife 42 from the slot 39, and uncovering the latter. The cam actuating the link 40 then causes a slight hesitation of the parts until the bristles have been removed from the picker by the descent of needle 47.

30 As the projection 48 continues in a counter-clockwise direction, it abuts shoulder 50 and thus urges the picker, with the bristle slot 39 open, in its upward movement. At the top of the stroke, the slot 39 has picked up enough bristles to form a tuft and the link 40 starts to descend, 35 the projection 48 traveling in slot 49 until it strikes shoulder 51, at which point the bristle slot 39 is closed, and the picker 23 starts its downward movement to the slot 45. It is to be noted that the picker 23 has a short dwell at each end 40 of its stroke due to the fact that the slot 49 is longer than the driving projection 48, and thus a lost motion connection is provided between the slide 41 and its knife 42, and the picker.

The bottom 21 is oscillated part of the time 45 through a slight arc to keep the bristles consolidated at the discharge end of the hopper and while at rest the picker slot 39 scoops the bristles into it, whereby this slot is filled while it is at an inclination. As the picker moves down to the 50 position shown and slightly beyond it, these bristles move down and the bristles are acted on in the usual way to form the tuft, as desired.

Having thus described my invention and the 55 advantages thereof, I do not wish to be limited to the details herein disclosed, otherwise than as set forth in the claims, but what I claim is:

1. In a bristle feeding device, the combination with a hopper for receiving the bristles having a tapering lower part, and a movable bottom for 60 controlling the area of the lower part, of means for intermittently vibrating said bottom to settle the bristles therein, means carried by said vibrating means for adjusting said bottom to limit said area, and a picker for gathering up enough bristles at a time to form a tuft when the bottom is not in motion.

2. In a bristle feeding device, the combination with a hopper for receiving the bristles having a movable bottom, of an oscillatable picker in position for engaging the bristles part way between

their ends over said bottom, means for oscillating said bottom to settle the bristles when the picker slot has moved out of the hopper, and a stationary member having a spring pressed plunger constantly engaging the surface of the picker for keeping the end of the hopper closed.

3. In a bristle feeding device, the combination with a hopper for receiving the bristles having a tapering lower part, a movable bottom for controlling the width of said lower part, and means for vibrating said bottom to settle the bristles in said lower part, of an oscillatory picker in position for engaging the bristles part way between their ends in said lower part and having a narrow opening in its edge for receiving from the hopper, on each backward stroke, enough bristles to form a tuft.

4. In a bristle feeding device, the combination with a hopper for receiving the bristles having a movable upwardly inclined bottom, and an opening of an oscillatory picker in position for its edge to engage the bristles part way between their ends and having a narrow opening in its edge for receiving therein from the hopper opening, on each backward stroke, enough bristles to 25 form a tuft, means for vibrating said bottom from a close to a remote position about an axis near one end, and yielding means for returning said bottom to its more remote position.

5. In a bristle feeding device, the combination with a hopper for receiving the bristles and a movable upwardly inclined bottom, of means for vibrating said bottom, of an oscillatory picker in position for engaging the bristles part way between their ends and having a narrow opening 30 in its edge for receiving from the hopper, on each backward stroke, enough bristles to form a tuft, means for vibrating said bottom from a close to a remote position about an axis near its upper end, yielding means for returning said bottom 35 to its more remote position, and adjustable means for limiting the retraction of the bottom.

6. In a bristle feeding device, the combination with a hopper for receiving the bristles having a tapering lower end and a movable bottom for 40 controlling the width of said lower end, of means for vibrating said bottom, an oscillatory picker in position for engaging the bristles in said bottom and having a narrow opening in its edge for receiving from the hopper, on each backward 45 stroke, enough bristles to form a tuft, a stationary member at the end of said bottom, and a spring pressed plunger in said member, for normally pressing the plunger into contact with the vibrating picker.

7. In a bristle feeding device, the combination with a hopper for receiving the bristles having a vibrating bottom, of a picker in position for engaging the bristles part way between their ends while they are on said bottom, said picker having 50 a narrow opening in its edge for receiving from the hopper, on each forward stroke, enough bristles to form a tuft, and a tuft doubling device located at a point to receive the bristles from said opening and double them into a tuft and force 55 the doubled tuft along a course to a point where they can be set.

8. In a bristle feeding device, the combination with a bristle hopper, of a reciprocable picker for engaging the bristles in the hopper and having a slot in its edge for receiving the bristles, a member slidably mounted on said picker and constructed and arranged to reciprocate said picker, there being a lost motion connection between said member and said picker whereby the 70

75

picker has a short dwell at one limit of its movement, and a slot closing element on said member.

5. In a bristle feeding device, a hopper, a picker reciprocably mounted for engagement with bristles in said hopper and having a bristle-receiving slot, an opening in said picker, a slide movably mounted on said picker and having a projection

shorter than said opening mounted therein, a slot-closing knife on said slide, means to reciprocate said slide and therefore said picker, the latter having a short dwell at its bristle-discharging station during which said slide and said knife 5 retreat from said slot to open the same.
